UNITED STATES PATENT OFFICE.

WILLIAM H. WHEELER AND THOMAS F. WHEELER, OF CAPE GIRARDEAU,
AND JOHN B. WHEELER AND CHARLES M. SLACK, OF JACKSON, MO.

SAMPLE-DISPLAYING LID.

SPECIFICATION forming part of Letters Patent No. 255,063, dated March 14, 1882.

Application filed November 1, 1881. (No model.)

To all whom it may concern:

Be it known that we, WILLIAM H. WHEELER and THOMAS F. WHEELER, of Cape Girardeau, in the county of Cape Girardeau and State of Missouri, and JOHN B. WHEELER and CHARLES M. SLACK, of Jackson, in the county of Cape Girardeau and State of Missouri, have invented a new and Improved Sample-Displaying Lid, of which the following is a full, clear, and exact description.

The object of our invention is to provide a new and improved sample-displaying lid for attachment to packages or cases containing merchandise.

The invention consists of a frame provided with a front glass and a wooden sliding back, between which the samples to be displayed are placed, which frame is hinged to the front end of the case or package by means of a hook 20 and a nut.

In the accompanying drawings, Figure 1 is a perspective view of a packing-case provided with our improved sample-displaying lid. Fig. 2 is a longitudinal sectional elevation of the 25 same.

Similar letters of reference indicate corresponding parts.

The frame A is provided with a glass slide, B, near its upper or outer surface, and with a 30 wooden or metal slide, C, near its lower or inner surface, these slides sliding in suitable grooves in the end pieces of the frame. This frame A is hinged to a strip, D, by means of a hinge, E, provided with a spring, F, for 35 pressing the frame A against the end or front of the case or package. A short rod, G, provided with a hook, H, at one end, and having the other end, J, threaded, is passed diagonally through the strip D. This strip D is 40 placed on that end of the packing-case K provided with an opening, L, and a lid, M, and the rod G is passed into the opening in such a manner that the hook H catches on the edge of the opening, this edge, or the edge of the 45 cover or lid M, being provided with a suitable notch or recess for the rod G.

The strip D is preferably provided with

pointed pins or detents d, for entering the wood of the case or package to hold the said strip D in place, and by means of a winged or 50 other nut, N, on the screw-threaded end J of the rod G, the strip D is pressed and held firmly on the end of the packing-case K.

The samples—for instance, cakes O—are placed on the lower slide, C, and the glass 55 slide B is then passed into the frame A. The samples will thus be held between the slides B and C, and are visible through the glass slide B.

The strip D can be secured on the case K 60 by means of one or more hooks, if desired. If any of the contents of the case K is to be removed, the frame A is raised or swung outward and the lid M is opened. As soon as the frame A is released it will be closed automatically by the spring F. This frame A can be used to display cakes, grain, spices, or any other kind of articles. The frame A is preferably provided with a ring or loop, D', for raising it. When the case K is empty the frame 70 A is removed and placed on another case, and the samples in the lid are changed accordingly.

If desired, the glass slide B may be replaced by a fixed glass top for the frame A; or the 75 glass may be made to slide, and the bottom C may be made rigid without materially changing our improved sample-displaying lid.

Having thus fully described our invention, what we claim as new, and desire to secure by 80 Letters Patent, is—

In combination with a packing-case, K, a sample-displaying lid consisting of the frame A, having the upper glass slide, B, and the lower slide, C, the said frame being hinged to 85 a detachable strip, D, as shown and described.

WILL. H. WHEELER.
